(57) **CLAIM**

The ornamental design for a baffle plate for a pipe expander as shown and described.

DESCRIPTION

FIG. 1 is a front side elevation view of a baffle plate for a pipe expander showing my new design.

FIG. 2 is front perspective view thereof.

FIG. 3 is a front side elevational view thereof.

FIG. 4 is a rear side elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken lines showing an example pipe expander in FIG. 1 are for the purpose of illustrating portions of the environmental structure and form no part of the claimed design.

1 Claim, 3 Drawing Sheets
